UNITED STATES PATENT OFFICE.

GEORGE A. MACKENZIE, OF BAY CITY, MICHIGAN.

GRATE.

Application filed April 28, 1919. Serial No. 293,349.

To all whom it may concern:

Be it known that I, GEORGE A. MACKENZIE, a citizen of the United States of America, residing at Bay City, in the county of Bay and State of Michigan, have invented certain new and useful Improvements in Grates, of which the following is a specification.

This invention relates to grates for furnaces and the like, adapted for use with furnaces particularly of the down draft type.

An object of the invention is to provide a grate which will readily burn any grade of fuel and which will leave nothing but a very fine ash adapted to naturally fall from the grate and into the ashpit.

Another object is to provide a suitable grate support upon which the grate proper is carried, and by oscillation of which the entire grate structure may be raised or lowered through instrumentality of an annular cam shoulder or support formed on the inner surface of the combustion chamber.

A still further object is to provide means for pre-heating air and introducing it to the grate to assist in consuming the soot and combustible gases which are ordinarily exhausted out of the chimney or exhaust flue.

These and other objects will appear as the description proceeds. In the drawings in which I have illustrated the preferred embodiment of my invention, and wherein similar reference characters designate corresponding parts throughout the several views;

Figure 1 is a vertical sectional view of my downdraft furnace, showing my improved grate in position therein.

Figure 2 is a plan view of the grate proper.

Figure 3 is a section taken on the line 3—3 of Fig. 2.

Figure 4 is a plan view of the grate support.

Figure 5 is a plan view of the cover for the grate support.

Figure 6 is a fragmentary side view, showing a fragment of the grate and its support.

Figure 7 is another side view showing a fragment of the cover and the grate without the grate support.

Figure 8 is a section taken on the line 8—8 of Fig. 2.

Figure 9 is a detail sectional view of one of the radiating arms of the grates.

Referring to the drawings, in which I

illustrate my improved grate as applied to a downdraft furnace, the grate 1 is seated and carried on the grate support 2 which is positioned within and carried by the combustion chamber 3, and while I show the grate as being supported by the walls of the combustion chamber, it will be readily understood that any other suitable means for accomplishing this may be employed and still lie within the scope of my invention.

The grate proper has as clearly shown in Figure 3 of the drawings, an opening 4 in the center thereof, in which the plug or member 5 is seated, said member having a shank 6 adapted to fit the opening 4 and a head 7 which extends upwardly and is conical in shape, and is designed to prevent the fuel from wedging and packing on the surface of the grate and to allow the air to circulate through the fuel.

Radiating from the center of the grate is a plurality of arms 8, terminating in a ring 9 cast integral with the grate, and provided with downwardly projecting concentric flanges 10 and 11 formed on the underside thereof.

The grate support is also annular in form, having a hollow hub member 12, which is adapted to be slidably seated on the hot air pipe 13, the said pipe extending downwardly and communicating with the outer air. Radiating from this hollow hub member 12 are the arms 14, extending to an annular air passage 15, which is formed by the upwardly extending concentric flanges 16 and 17, the outer flange 16 being of a greater height than the inner flange, and fitting against the inside of the outer flange 11 formed on the underside of the grate 1, said flange 16 having a series of notches 16^a formed therein designed to allow air to escape into the combustion chamber of the furnace. The arms 14 are formed substantially as shown in Fig. 9 of the drawings, the sides thereof being also formed with openings 18 to allow a portion of the pre-heated air to escape therefrom. Located on the underside of these members 14 are the supporting legs 19. These legs extend outwardly and downwardly as shown, and are designed to rest on the annular shoulder 20 on the inner wall of the combustion chamber 3. The shoulder 20 has spaced notches or recesses 20^a with inclined sides and provides an undulating or cam trackway to raise the grate 1 when the latter is turned

or oscillated to provide sufficient space beneath the grate to remove slate or other foreign matter from the surface of the grate, the grate otherwise being self cleaning as the fine ash will readily fall therefrom.

Seated and carried on the arms 14 of the grate support is the cover 21, forming a closure or cap for the hub and the perforated arms of the grate support, to prevent the 10 ashes from falling into same and filling the openings through which the pre-heated air is adapted to flow, said member being also formed with arms 22 extending radially from the center thereof and formed with the 15 downwardly extending edges 22^a as clearly shown in section in Fig. 5. The cover 21 has an upstanding rim or flange 23 which is formed integral therewith, and when in position is adapted to be seated outside of the flange 10 formed on the under side of the grate. This flange 23 also has notches 24 through which the pre-heated air is adapted to escape into the combustion chamber, and it will be apparent that the grate proper is seated on and carried by the flange 16 and the cover 21 is supported on the flange 17.

The air is introduced into the furnace 25 through the air passage or pipe 13, which extends into the ashpit 26 and up into the combustion chamber 3 of the furnace, and it will be obvious that the heat in the combustion chamber will readily pre-heat the air as it flows to the grate. The air flows through the passages in the grate and its support as above pointed out, and into the combustion chamber 3 around the outer edge of the grate proper and inwardly toward the interior of the grate; thence circulating up and into the fuel to assist in the complete 35 consumption of all soot and combustible gases, and, in actual practice leaving nothing but a very fine ash which will readily fall through the grate. To shake the grate a suitable implement is engaged with one of the legs 19 and moved back and forth horizontally, whereby the legs 19 ride over the cams of shoulder 20 and raise and lower the 45 grate.

From the foregoing description it will be 50 obvious that I have perfected a simple and economical grate, which will burn any grade of fuel and which can be quickly and easily removed in sections when desired.

What I claim is:

55 1. In a furnace, a grate body having spaced depending flanges, a support for said grate body having hollow arms and a hollow ring mounted on the outer ends of the arms and communicating therewith, said 60 ring having an upstanding flange adapted to fit against one of the flanges of said grate

body and the flange of the ring having openings therethrough, a cover for closing the upper sides of said arms and having a flange arranged to engage the other flange of the grate body and having openings therethrough, and means for placing the hollow arms in communication with a source of heated air.

2. In a furnace, a grate body having depending spaced flanges, a support having hollow radial arms with a hollow ring support on the outer ends of the arms and provided with an upstanding flange at the outer edge of the ring, said arms and ring being open at their upper sides, and a removable cover arranged to seat over said arms and having an upstanding flange at the outer edge of the cover spaced inwardly from the flange of the ring and forming a continuation of the ring, said flanges of the ring and the cover having openings therethrough to permit air to escape from the ring and said last named flanges being adapted to engage with the flanges of the grate body and to support the latter.

3. In a furnace, a gate body, a support for said grate body comprising hollow radial arms and a hollow ring carried upon the outer ends of the arms and communicating therewith, a removable cover part for said arms and ring, and the cover part and the ring having upstanding spaced flanges forming an annular air space above the ring and the flanges having openings therein through which air may pass, said flanges being adapted to receive the grate body thereon for supporting the grate body and for distributing air therebeneath.

4. In a furnace, a grate body having spaced annular depending flanges, a support for said grate body comprising a plurality of radially disposed hollow arms and a hollow ring carried upon the outer ends of the arms and communicating therewith, said ring having its outer wall extended upwardly and providing a flange adapted to fit between the depending flanges of the grate body for supporting the latter, a cover for the hollow arms having an annular upstanding flange forming a continuation of the inner wall of the ring and arranged to fit between said depending flanges of the grate body to support the same, and means for placing the hollow arms in communication with a source of heated air, said flanges of the ring and cover having openings in their upper portions for distributing the heated air beneath the grate body.

In testimony whereof I affix my signature.

GEORGE A. MACKENZIE.
